UNITED STATES PATENT OFFICE.

LEWIS T. RHOADES, OF MONT CLARE, PENNSYLVANIA.

CURRENT-CONTROLLING MECHANISM FOR INTERNAL-COMBUSTION ENGINES.

1,028,277.

Specification of Letters Patent. Patented June 4, 1912.

Application filed September 16, 1911. Serial No. 649,631.

To all whom it may concern:

Be it known that I, LEWIS T. RHOADES, a citizen of the United States, residing at Mont Clare, in the county of Montgomery and State of Pennsylvania, have invented 5 certain new and useful Improvements in Current-Controlling Mechanism for Internal-Combustion Engines, of which the following is a specification.

10 My invention relates to improvements in current controlling mechanism for internal combustion engines, the object of the invention being to provide improved mechanism which insures a uniform spark, regardless of the speed of the engine, and 15 which prevents sparking when the engine time shaft is turned in a reverse direction.

A further object is to provide improved 20 means continuously revolved by the time shaft and imparting to a contact operating member an oscillatory movement in two directions, and provide a spring for returning said contact closing member to normal 25 position, and causing it on such return movement to close the contacts.

With these and other objects in view, the 30 invention consists in certain novel features of construction and combinations and arrangements of parts, as will be more fully hereinafter described and pointed out in the claims.

In the accompanying drawings: Figure 1, 35 is a plan view of my improvements with the casing removed. Fig. 2, is a view in elevation with the structure shown in Fig. 1 illustrating in addition the casing in section and the contact operating head in elevation. Fig. 3, is a view similar to Fig. 1 showing the parts in different positions. 40 Fig. 4, is a view similar to Fig. 2 omitting the casing, and showing the parts in the position shown in Fig. 3. Fig. 5, is a view in longitudinal section on the line 5—5 of Fig. 4. Fig. 6, is a view in horizontal section on 45 the line 6—6 of Fig. 2, and Figs. 7, 8, 9, 10, 11, and 12 are perspective views of various details of construction.

While of course a mechanism of this character may be variously positioned, and there 50 is no such thing as vertical and horizontal with relation to the parts, for convenience of description I believe it advisable to so refer to the parts because of the different movements imparted to the contact closing 55 member, and the description hereinafter will consider the parts as positioned in Figs. 2,

4, and 5, with relation to vertical and horizontal, but of course these parts may be just reversed or placed in any position which is most convenient to the engine or 60 mechanism with which it is used.

1, represents a supporting plate we will assume to be horizontal, and which is provided on its under face with an integral bearing sleeve 2 through which a journal 3 projects, which we understand to be vertical. The lower end of this journal 3 is enlarged as shown at 4 to bear against the end of sleeve 2, and said journal is provided with a recess 5 for the reception of the time shaft (not shown), which is to be secured in the recess by means of set screws 6. The journal 3 is provided with an annular lubricant receiving groove 7, and a check valve 8 is provided in the side of the sleeve 2, through which lubricant may be supplied to the journal. The upper end of journal 3 above plate 1, is of greatly reduced diameter as shown at 9, and is screw-threaded at its upper end for the reception of a nut 10. 70 The journal 3, at a point in line with the upper face of platform 1, is also shouldered as shown at 11 against which a ring 12 of fiber is positioned, and between this ring 12 and the nut 10, my improved rotary member 13 is located. The rotary member 13 is preferably made in two parts 14 and 15, both of which constitute rings adapted to receive the restricted upper end 9 of the journal 3, and the lower ring 15 being of 80 greater diameter than the upper ring 14. These rings 14 and 15 are made with registering openings 16 for the reception of a pin 17, said pin 17 also projecting into a recess 18 in the journal 3, and hence not 85 only holds the two rings 14 and 15 to compel them to turn together, but also securely keys them to the journal.

The nut 10 above referred to is provided with two spanner wrench receiving openings 19, and normally in one of these openings a pin 20 is positioned. The pin projects through an opening 19, and at its lower end extends into a recess 21 in upper ring 14, and the upper end of said pin projects above the nut and into a recess 22 in a head 23. The head 23 is of insulating material and carries thereon a spring contact piece 24, and the latter serves to connect a central contact 25 in a hood 26 with a circular series of contacts 27 also in said hood, and adapted to be connected with the sev-

eral cylinders of the engine. The hood 26 is grooved at its lower edge to receive the plate 1, and is provided with screw-threaded studs 28 on which nuts 29 are located to 5 hold the hood in position on the plate.

A supporting tongue 30 is secured to the plate 1 by screws 31, and is adapted for attaching the mechanism to its support (not shown). A vertically positioned binding 10 post 32 extends through plate 1, is insulated therefrom as shown at 33, and is provided with a stationary contact 34 adapted to be engaged by a contact 35 on a movable contact member 36. The member 36 constitutes 15 a bar 37 having a hooked end 38 against which a spring 39 normally bears. This spring 39 carries the contact 35 and said spring and said arm are both secured by means of a screw 40 to a block 41. The 20 block 41 has rotary mounting on a vertical pin 42 fixed to plate 1, and a coiled spring 43 connects the end of the screw 40 with an eye 44 on plate 1. The spring 43 is so positioned that it tends to turn the block 41 25 and hold the contacts apart, the movement in this direction being limited by a pin 45 against which the bar 37 engages. Therefore, as above set forth, for convenience of description, we will assume that the movable contact has a horizontal oscillatory 30 movement.

Between the rotary member 13 and the movable contact member 36, is my improved contact moving member which is operated 35 by the rotary member to intermittently move the contacts together. The contact moving member is shown in perspective in Figs. 8, and 9, and it constitutes a lever 46 having a journal pin 47 at one end mounted 40 to turn in a block 48, and securely held in said block by means of a cotter pin 49. Block 48 has rotary mounting on a vertical pin 50 secured to plate 1, and hence the said lever 46, or contact moving member as I 45 shall hereinafter refer to it, is permitted an oscillatory movement in two directions. One direction I shall consider for convenience of description as "up and down" and the other as "in and out," and these terms 50 are used with relation to the journal 3 and the rotary member thereon, assuming that said journal is disposed vertically.

A laterally projecting arm 51 is provided 55 on the member 46, and is connected by a coiled spring 52 with an eye 53 secured to plate 1. This spring is positioned at such an angle that it exerts an inward as well as a downward pressure on the member, tending to hold the same in the position shown 60 in Fig. 1, the movement of said lever or member 46 by the spring being limited in one direction by a pin 63, while the downward movement of said members is limited by the ring 12.

65 The member 46 is provided in its lower

face between its ends, with a cut-out portion 54, and the wall of said cut-out portion, adjacent the free end of the member, is beveled forming a cam face 55. The free end of the member 46 is preferably bent backward upon itself as shown at 56, and this bent end is located at an angle forming a cam surface 57 for a purpose which will hereinafter appear. The bent end is narrower than the main portion of the member, 70 and an inclined cam face 58 is formed adjacent the forward end of said member. The bar 37 above referred to constitutes a part of the movable contact member, and as shown in perspective in Fig. 7 is provided with a cut-out portion 59 and a laterally projecting tongue 60 constituting a cam face. These several cam faces each have their particular function, and control the motion imparted by the rotary member 85 13 to the contact moving member 46.

Both of the sections 14 and 15 of the rotary member 13 are provided with circular series of cams 61 and 62 respectively, and the cams of one section are fixed with operative relation to the other, as seen most clearly in Figs. 1 and 3. Cams 62 on the lower section 15 are of general triangular shape, and when the time shaft is turning in the proper or normal direction, these 95 cams engage the cam face 58 of member 46, and elevate the free end of said member 46. When, however, the time shaft is turned in the reverse direction, the straight walls of said cams 62 will engage the cam face 55 100 and force member 46 outwardly without elevating the same, this motion being permitted by the cut-out portion 59 of the bar 37. The cams 61 on the upper section 14 are adapted, when member 46 is elevated by 105 the cam 62, to engage the cam face 57 of the member 46 and force the member 46 outwardly, while said member 46 is held in an elevated position by means of the cam 62 below. As soon, however, as the cam 62 110 rides from under the member 46, spring 52 will draw the member 46 downwardly and inwardly. This last movement compels the end 56 of the member 46 to strike the cam tongue 60 and force the movable contact laterally to momentarily close the contacts. This movement of member 46 is always the same, regardless of the speed of the engine. In other words, the contacts are maintained closed for the same length of time when the 115 engine is running fast as when running slow, because the speed of the time shaft does not control this movement of member 46.

Spring 52 causes the member 46 to move 120 downwardly and inwardly as soon as released, and at the same speed when the rotary member is turning fast or slow, hence the contacts are always closed the same length of time. They are closed only dur- 125 130

ing the brief space of time the member 46 presses against the tongues 60 in the downward and inward movement of said member, hence there is no waste of electric current and the desired spark is had.

The contact member 46 is held outward during its downward stroke in accordance with the length or vertical dimension of the cams 61, and this dimension is sufficient to make the necessary contact. It will therefore be noted that in the normal running of the mechanism, the rotary member causes the contact moving member to receive an oscillatory motion in two directions, first, a vertical movement, and then an outward movement. The downward and inward movement caused by the spring 52 compels the member 46 to close the contacts. When the time shaft turns in a reverse direction, the contacts are not closed, because the cams 52 will simply throw the free end of member 46 outwardly without elevating said member into the path of cams 61.

It is of course to be understood that the cams 61 and 62 will be in number and arrangement in accordance with the number of cylinders to be fired, each cylinder being fired at every revolution of the time shaft.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

40 1. In a device of the character described, the combination with electric contacts normally apart, of a rotary member, a pivotally mounted contact moving member, means on said rotary member constructed to move the contact moving member in two directions, and a spring constructed to return said contact moving member to normal position and during such return movement close said contacts, substantially as described.

45 2. In a device of the character described, the combination with electrical contacts normally apart, of a rotary member, a contact moving member, means on said rotary member constructed to move said contact moving member in two directions, and a spring constructed to move said contact moving member in a third direction, and said parts so constructed as to move said contacts together during said last-mentioned movement, substantially as described.

50 3. In a device of the character described, the combination with a fixed contact, and a movable contact normally spaced from the fixed contact, of a rotary member, a contact moving member, a cam block on said rotary

member constructed to move the contact moving member in one direction, a second cam on said rotary member constructed to move the contact moving member in a second direction when moved by the first-mentioned cam, and a spring constructed to move said contact moving member in a third direction, and move said contacts together during said last-mentioned movement, substantially as described. 70

4. In a mechanism of the character described, the combination with contacts normally apart, of a movable member to which one of said contacts is secured, a cam tongue on said member, a rotary member, a contact moving member, cams on said rotary member constructed to move said contact moving member in two directions, and a spring constructed to move said contact moving member in a third direction and during said last-mentioned movement engage the cam tongue and force the contacts momentarily together, substantially as described. 75

5. In a mechanism of the character described, the combination with contacts normally apart and a cam face on one of said contacts, of a contact moving member, a rotary member, a series of cams on said rotary member constructed to normally move the contact moving member in one direction and when turned in a reverse direction move said contact moving member in a different direction, a second series of cam blocks on the rotary member constructed to move the contact moving member into position in line with the said cam face, and a spring constructed to draw said contact moving member across said cam face during the return movement of said contact moving member and force the contacts momentarily together, substantially as described. 90

6. In a mechanism of the character described, the combination with a stationary contact, a pivoted spring held bar, a contact on said bar, and a cam face on said bar, of a rotary member having cams thereon in different planes, a contact moving member pivotally supported to oscillate in two directions, a cam face on said contact moving member in the path of movement of one of said cams on the rotary member, whereby said cam serves to oscillate said contact moving member in one direction into the path of movement of the other cam and the latter moves said contact moving member in a second direction, and a spring constructed to draw said contact moving member to normal position, and in such movement engage the cam face on the bar and 110 momentarily move the contacts together, substantially as described. 115

7. In a mechanism of the character described, the combination with a stationary contact, a pivoted bar, and a movable con- 120

125

tact on said pivoted bar, of a spring normally holding said bar in position to maintain the contacts apart, a cam face on said bar, a rotary member, two circular series of cams on said rotary member in different planes, a contact moving member, a cam face on said contact moving member adapted to be engaged by one set of said cams during the normal direction of movement of said rotary member to elevate the contact moving member into the path of the other set of cams, said last-mentioned set of cams constructed to move said contact moving member outwardly and over the cam face on the bar, and a spring constructed to move said contact moving member across said cam face of the bar and back to normal position, substantially as described.

8. In a mechanism of the character described, the combination with a stationary contact, a pivoted bar, and a movable contact on said pivoted bar, of a spring normally holding said bar in position to maintain the contacts apart, a cam face on said bar, a rotary member, two circular series of cams on said rotary member in different planes, a contact moving member, a cam face on said contact moving member adapted to be engaged by one set of said cams during the normal direction of movement of said rotary member to elevate the contact moving member into the path of the other set of cams, said last-mentioned set of cams constructed to move said contact moving member outwardly and over the cam face on the bar, and a spring constructed to move said contact moving member across said cam face of the bar and back to normal position, said contact moving member having a cam face adapted to be engaged by the first-mentioned set of cams to move the contact moving member outwardly without moving the contacts when said rotary member is turned in a reverse direction, substantially as described.

9. In a device of the character described, the combination with electric contacts normally apart, of a rotary member, a contact moving member, means on said rotary member constructed to move the contact moving member, a spring constructed to return said contact moving member to normal position and during such return movement close said contacts, a supporting plate to which said contacts and contact moving member are connected, a journal having rotary mounting in said plate and to which said rotary member is connected, a casing secured on said plate, a central contact in said casing, a circular series of contacts around said central contact, a head of insulating material on said journal, and a metal contact on said head adapted to alternately connect the central contact with the contact of the circular series, substantially as described.

10. In a device of the character described, the combination with electrical contacts normally apart, of a rotary member, a contact moving member, means on said rotary member constructed to move said contact moving member in two directions, a spring constructed to move said contact moving member in a third direction, and said parts so constructed as to move said contacts together during said last-mentioned movement, a supporting plate to which said contacts and contact moving member are connected, a journal having rotary mounting in said plate and to which said rotary member is connected, a casing secured on said plate, a central contact in said casing, a circular series of contacts around said central contact, a head of insulating material on said journal, and a metal contact on said head adapted to alternately connect the central contact with the contact of the circular series, substantially as described.

11. In a device of the character described, the combination with a fixed contact, and a movable contact normally spaced from the fixed contact, of a rotary member, a contact moving member, a cam block on said rotary member constructed to move the contact moving member in one direction, a second cam on said rotary member constructed to move the contact moving member in a second direction when moved by the first-mentioned cam, and a spring constructed to move said contact moving member in a third direction, and move said contacts together during said last-mentioned movement, a supporting plate to which said contacts and contact moving member are connected, a journal having rotary mounting in said plate and to which said rotary member is connected, a casing secured on said plate, a central contact in said casing, a circular series of contacts around said central contact, a head of insulating material on said journal, and a metal contact on said head adapted to alternately connect the central contact with the contact of the circular series, substantially as described.

12. In a mechanism of the character described, the combination with contacts normally apart, of a movable member to which one of said contacts is secured, a cam tongue on said member, a rotary member, a contact moving member, cams on said rotary member constructed to move said contact moving member in two directions, and a spring constructed to move said contact moving member in a third direction and during said last-mentioned movement engage the cam tongue and force the contacts momentarily together, a supporting plate to which said contacts and contact moving member are connected, a journal having rotary mounting in said plate and to which said rotary member is connected, a casing secured on

said plate, a central contact in said casing, a circular series of contacts around said central contact, a head of insulating material on said journal, and a metal contact on said 5 head adapted to alternately connect the central contact with the contact of the circular series, substantially as described.

13. In a mechanism of the character described, the combination with contacts normally apart and a cam face on one of said 10 contacts, of a contact moving member, a rotary member, a series of cams on said rotary member constructed to normally move the contact moving member in one 15 direction and when turned in a reverse direction move said contact moving member in a different direction, a second series of cam blocks on the rotary member constructed to move the contact moving member into 20 position in line with the said cam face, a spring constructed to draw said contact moving member across said cam face during the return movement of said contact moving member and force the contacts momentarily 25 together, a supporting plate to which said contacts and contact moving member are connected, a journal having rotary mounting in said plate and to which said rotary member is connected, a casing secured on 30 said plate, a central contact in said casing, a circular series of contacts around said central contact, a head of insulating material on said journal, and a metal contact on said head adapted to alternately connect the central contact with the contact of the circular series, substantially as described.

14. In a mechanism of the character described, the combination with a stationary contact, a pivoted spring held bar, a contact 40 on said bar, and a cam face on said bar, of a rotary member having cams thereon in different planes, a contact moving member pivotally supported to oscillate in two directions, a cam face on said contact moving 45 member in the path of movement of one of said cams on the rotary member, whereby said cam serves to oscillate said contact moving member in one direction into the path of movement of the other cam and the latter 50 moves said contact moving member in a second direction, a spring constructed to draw said contact moving member to normal position, and in such movement engage the cam face on the bar and momentarily move 55 the contacts together, a supporting plate to which said contacts and contact moving member are connected, a journal having rotary mounting in said plate and to which said rotary member is connected, a casing 60 secured on said plate, a central contact in said casing, a circular series of contacts around said central contact, a head of insulating material on said journal, and a metal contact on said head adapted to alternately 65 connect the central contact with the contact

of the circular series, substantially as described.

15. In a mechanism of the character described, the combination with a stationary contact, a pivoted bar, and a movable contact on said pivoted bar, of a spring normally holding said bar in position to maintain the contacts apart, a cam face on said bar, a rotary member, two circular series of cams on said rotary member in different planes, a contact moving member, a cam face on said contact moving member adapted to be engaged by one set of said cams during the normal direction of movement of said rotary member to elevate the contact moving 80 member into the path of the other set of cams, said last-mentioned set of cams constructed to move said contact moving member outwardly and over the cam face on the bar, a spring constructed to move said contact moving member across said cam face of the bar and back to normal position, a supporting plate to which said contacts and contact moving member are connected, a journal having rotary mounting in said 90 plate and to which said rotary member is connected, a casing secured on said plate, a central contact in said casing, a circular series of contacts around said central contact, a head of insulating material on said 95 journal, and a metal contact on said head adapted to alternately connect the central contact with the contact of the circular series, substantially as described.

16. In a mechanism of the character described, the combination with a stationary contact, a pivoted bar, and a movable contact on said pivoted bar, of a spring normally holding said bar in position to maintain the contacts apart, a cam face on said bar, a rotary member, two circular series of cams on said rotary member in different planes, a contact moving member, a cam face on said contact moving member adapted to be engaged by one set of said cams during the normal direction of movement of said rotary member to elevate the contact moving member into the path of the other set of cams, said last-mentioned set of cams constructed to move said contact moving 105 member outwardly and over the cam face on the bar, a spring constructed to move said contact moving member across said cam face of the bar and back to normal position, said contact moving member having a cam face 110 adapted to be engaged by the first-mentioned set of cams to move the contact moving member outwardly without moving the contacts when said rotary member is turned in a reverse direction, a supporting plate to 115 which said contacts and contact moving member are connected, a journal having rotary mounting in said plate and to which said rotary member is connected, a casing secured on said plate, a central contact in 120

125

130

said casing, a circular series of contacts around said central contact, a head of insulating material on said journal, and a metal contact on said head adapted to alternately connect the central contact with the contact of the circular series, substantially as described.

In testimony whereof I have signed my name to this specification in the presence of two subscribing witnesses.

LEWIS T. RHOADES.
